UNITED STATES PATENT OFFICE

104,673

DESIGN FOR TYPE FONT

Fritz L. Amberger, New York, N. Y.

Application March 20, 1937, Serial No. 68,305

Term of patent 3½ years

To all whom it may concern:

Be it known that I, Fritz L. Amberger, a citizen of Switzerland, residing in the city of New York, county of New York, and State of New York, United States of America, have invented a new, original, and ornamental Design for Type Font, of which the following is a specification, reference being had to the accompanying drawing, forming a part thereof, in which the figure of the drawing shows a face view of the type font embodying my design.

The type font is characterized by disconnected portions, serifs, and light and heavy strokes as shown.

I claim:

The ornamental design for type font, as shown and described.

FRITZ L. AMBERGER.
